UNITED STATES PATENT OFFICE

172,279

LUBRICATING EQUIPMENT CABINET

William H. Joachim, Rockville Centre, N. Y.

Application October 16, 1953, Serial No. 27,205

Term of patent 14 years

(Cl. D52—2)

To all whom it may concern:

Be it known that I, William H. Joachim, a citizen of the United States, residing in Rockville Centre, in the county of Nassau and State of New York, have invented a new, original, and ornamental Design for a Lubricating Equipment Cabinet, of which the following is a specification, reference being had to the accompanying drawing, forming part thereof.

Fig. 1 is a perspective view taken from the side and somewhat from the front of a lubricating equipment cabinet showing my new design.

Fig. 2 is a perspective view taken from the side and rear of the cabinet with the covers in closed condition.

Fig. 3 is a front perspective view thereof, and
Fig. 4 is a rear view thereof.

The side of the lubricating equipment cabinet not shown is substantially the same in appearance as the side disclosed.

I claim:

The ornamental design for a lubricating equipment cabinet, substantially as shown and described.
